UNITED STATES PATENT OFFICE.

HENRY HOWSON, OF PHILADELPHIA, PENNSYLVANIA, ASSIGNOR TO PROCTOR & SCHWARTZ, INCORPORATED, OF PHILADELPHIA, PENNSYLVANIA, A CORPORATION OF PENNSYLVANIA.

DRIER.

1,404,614.

Specification of Letters Patent. Patented Jan. 24, 1922.

Application filed October 13, 1920. Serial No. 416,627.

To all whom it may concern:

Be it known that I, HENRY Howson, a citizen of the United States, residing in Philadelphia, Pennsylvania, have invented 5 certain improvements in Driers, of which the following is a specification.

My invention relates to certain improvements in apparatus for drying material by the circulation of heated air.

10 The invention can be applied to apparatus for drying material supported on trays, suspended from rods, or carried by endless conveyers.

One object of the invention is to locate the 15 circulating fan, or fans, at an angle, preferably at the corner of the drier and at one side of the heating chamber.

20 A further object of the invention is to construct the fan so that the bearings for the fan shaft are accessible as they are on the outside of the casing.

A still further object of the invention is to locate the bearings so that they will be protected from the direct action of the heat.

25 Still another object of the invention is to provide a construction by which the fan can be bodily moved out of the apparatus without disconnecting the gearing in order that minor repairs may be made to the fan structure.

30 In the accompanying drawings:

Fig. 1 is a sectional view through a drier, illustrating my invention;

35 Fig. 2 is a side view of sufficient of a drier illustrating my invention to show the power shaft and the fan shaft;

Fig. 3 is a view illustrating the fan structure located at the lower portion of the drier; and

40 Fig. 4 is a view of a modification in which the fan shaft extends through the casing at both ends.

Referring to the drawings, 1 is the casing divided by a vertical partition 2 into a drying chamber 3 and a circulating chamber 4.

45 In the upper portion of the drier, in the present instance, is a heating chamber 5, in which is a series of steam pipes 6, which heat the air in circulation. 7, 7 are trays 50 adapted to travel on rails 8 of any suitable form. The drying chamber is separated from the heating chamber by a partition 9, which extends part-way across the drier,

leaving a space 10 for the free circulation of air.

55 11 is a fan shaft mounted in bearings 12 secured to a base 13, which is firmly secured to the recessed portion 14 of the frame 1^a of the casing. This frame is movably located in the frame 1 of the drier and the shaft 11 60 has a fan 15 at its inner end and a right-angled gear wheel 16 at its outer end, which meshes with a like wheel 17 on a longitudinal power shaft 18 adapted to bearings 19 secured to the frame work of the casing 1. 65 The fan is enclosed within an annular ring 20 made in two parts in the present instance. The part 20^a is fixed, while the part 20^b is secured to the movable frame 1^a of the casing, the dividing line being at the center of the 70 ring.

It will be noticed that the frame 1 is recessed from the outside, as at 21, and the bearings 12 are located in this recess. The casing 14 of the frame separates this recess 75 from the interior of the drier, consequently, the bearings are kept cool at all times. A collar 22 is secured to the shaft 11 and a ball bearing may be provided at this point, if desired. The casing of the frame 1^a overlaps the main frame at top and bottom and at the sides, as shown, so that when it is in place it forms a continuation of the casing. The portion 14 of the frame, which extends into the drier, is comparatively narrow so 85 as not to interfere with the circulation of air in the drier, as clearly shown in Fig. 2.

In Fig. 3, I have shown a modification in which the fan is located at one of the lower corners of the drier and the heating chamber 5^a also forms the circulating chamber. In this chamber is a series of heating pipes 6^a. If desired, heating pipes 6^b may be located in the lower portion of the drier, as shown in the drawings. In this instance, 90 the portion carrying the bearings is a continuation of the main frame and is not movable.

In Fig. 4, another modification is illustrated, in which the bearings are located on 100 the outside of the casing, the bearing 12^a being located on the top of the casing and the bearing 12^b being located at the side of the casing. The diagonal shaft 11^a extends through the casing and is mounted in the bearings. About midway between the two bear- 105

ings is the fan 15^a situated in an opening formed by a ring 20^e in the diagonal partition 23.

When power is applied, the fan is rotated 5 and the air circulates as indicated by the arrows, Fig. 1, passing between the heating pipes and down through the circulating chamber and up through the drying chamber, drying the material carried by the trays, 10 or other supports.

By locating the fan in the manner shown, the bearings are on the outside of the drier and are protected from the heat, consequently, the bearings can be properly lubricated at all times. Lubricant can be applied 15 from the outside of the drier while the machine is in operation.

By making the frame, which carries the bearings, movable, the frame, with the fan 20 and the shaft, can be turned on the power shaft or its bearing as a pivot so that, in the event of any repairs being necessary to the fan, they can be made without entering the drier.

25 While only one fan is shown and the structure connected therewith, a drier may be provided with a series of fans, depending upon the length of the drier and the material to be dried.

30 I claim:

1. The combination of a drier having a drying compartment; means for heating the air in said compartment; a fan for circulating the air through the compartment; a shaft on which the fan is mounted, said shaft being arranged at an angle in 35 respect to the horizontal; and bearings for the fan shaft on the outside of the casing.

2. The combination in a drier, of a drying 40 chamber; a circulating chamber; means for heating the air in circulation; a diagonally arranged shaft at one corner of the drier; a fan on the shaft for causing the air to circulate through the drying chamber and 45 through the circulating chamber, the bearings for said shaft being on the outside of the casing; and a power shaft, also on the outside of the casing, geared to said fan shaft.

50 3. The combination in a drier, of a drying chamber; means for circulating air in the chamber; a diagonally arranged shaft; bearings for said shaft, said bearings being on the outside of the casing; a support for the 55 bearings, said support projecting into the drier; and a fan mounted on the shaft within the drier.

4. The combination of a drier having a drying chamber and a circulating chamber; means for heating the air in circulation in 60 said chamber; a fan; a shaft on which the fan is mounted; bearings for the shaft; a support for the bearings; and a longitudinal power shaft by which the fan is driven, the bearings being on the outside of the 65 casing of the drier, the supports for the bearings and the fan being movable so as to allow the fan to be moved to the outside of the casing.

5. The combination in a drier, of a partition separating the drier into a drying chamber and a circulating chamber; a diagonal shaft; a fan mounted on the shaft located between the drying chamber and the circulating chamber; a longitudinally arranged power shaft; gearing for driving the fan shaft from the power shaft; bearings for the said shaft; and a frame on which the bearings are mounted projecting into the drier, the said structure being piv- 75 otally mounted at the power shaft so that, when desired, the structure can be turned on the power shaft to move the fan to the outside of the drier.

6. The combination in a drier, of a vertical partition separating a drying chamber from a circulating chamber; a heating chamber above the drying chamber; heating pipes therein; a diagonally arranged partition separating the heating chamber from the 90 circulating chamber; said partition having an opening; a fan located in the opening; a diagonal shaft on which the fan is mounted; bearings for the fan shaft; means for driving the shaft; and a casing separating 95 the bearings from the fan and from the interior of the drier so that the bearings are on the outside, while the fan is within the drier.

7. The combination in a drier, of a vertical partition; a diagonal partition separating the drier into compartments; means for heating the air in circulation in the compartments; a movable frame forming part of the casing; a segmental ring mounted partly on the fixed frame of the casing and 100 partly on the movable frame and forming a fan opening; a fan located in said opening; a diagonal shaft on which the fan is mounted; bearings for said shaft; means for driving the shaft; and a pivot for the 105 fan structure, including a frame, so that the structure can be turned on the pivot to move the fan to a position outside of the drier.

HENRY HOWSON.
